(57) **CLAIM**

The ornamental design for a portable electronics enclosure, as shown and described.

DESCRIPTION

FIG. 1 is a perspective view of a portable electronics enclosure showing our new design;

FIG. 2 is a top plan view thereof;

FIG. 3 is a bottom plan view thereof;

FIG. 4 is a front elevational view, the rear elevational view being a mirror image thereof;

FIG. 5 is a side elevational view of one side, the opposite side elevational view being a mirror image thereof; and,

FIG. 6 is a perspective view thereof shown in stacked formation.

The broken line showings of the rectangular area on the top and bottom surfaces, the circles at the corners of the bottom surface and the bottom component in FIG. 6 are for illustrative purposes only and form no part of the claimed design.
